BROAD-BAND DIRECTIVE ANTENNA

Oakley M. Woodward, Jr., Princeton, N. J., assignor to Radio Corporation of America, a corporation of Delaware

Application April 3, 1951, Serial No. 218,986

4 Claims. (Cl. 250—33.53)

1

This invention relates to a broad-band antenna and more particularly to an antenna suitable for use in the ultra-high frequency band.

It is an object of this invention to provide an improved ultra-high frequency dipole antenna having separated arms and a broad frequency band characteristic.

It is a further object of this invention to provide a mechanically stable, all metal ultra-high frequency receiving antenna of the dipole type with electrically conducting bridging means between the effective electrical centers of the dipole arms.

According to one embodiment of this invention, two similarly constructed triangular sheets of conductive material are arranged substantially in the same plane with an apex of one sheet forming an acute angle adjacent to the corresponding apex of the other sheet also forming an acute angle. The dimension across both sheets is approximately in the range from $\frac{3}{8}$ to $\frac{5}{8}$ of the operating wave length. A conductive strap of approximately half this length is rigidly secured to the back of the sheets of material at the centers thereof and the center section of the strap is spaced away from these elements. The strap serves a dual purpose, first as a support for the antenna, and second as a shunt reactance in parallel with the antenna. The transmission line to the antenna is connected at or very near the adjacent apexes.

According to another embodiment of the invention, an array of these antennas is provided by arranging two or more of these antenna constructions in a single plane and mechanically and electrically connecting the lower outer points of the triangular sheets of one dipole antenna with the upper outer points of the triangular sheets of another dipole element, assuming that the antenna array is in the vertical plane. A short length of line is used to connect the adjacent apexes of each dipole antenna in the array with those of the other dipole antennas. The transmission line extending from the antenna to suitable transducer apparatus, such as a transmitter or receiver, is connected to the center of this short length of line.

Other objects and advantages will be apparent from reading the following specification in connection with the accompanying drawing, in which:

Fig. 1 is a front elevation of the antenna;

Fig. 2 is a bottom view of the antenna;

Fig. 3 shows the gain over a portion of the ultra high frequency band;

Fig. 4 shows the standing wave ratio over the same portion of the band;

2

Fig. 5 shows the field patterns of the antenna at the lower end of the ultra high frequency band;

Fig. 6 shows the field pattern at a higher frequency;

Fig. 7 illustrates an array of the elements shown in Fig. 1;

Fig. 8 shows the gain over a portion of the ultra high frequency band for the array shown in Fig. 7;

Fig. 9 shows the standing wave ratio for the same array; and

Figs. 10 and 11 show the field patterns given by the array for the same frequencies shown in Figs. 5 and 6.

In the drawing, the same reference characters designate the same or similar parts in the several views.

In Fig. 1 there are shown two triangular sheets of conductive material 11 having adjacently positioned apexes to which a transmission line may be connected at feed point 13. Each sheet 11 has diverging sides forming an acute angle A. The angle of each sheet determines the broad band frequency range. An electrically conductive strap 15 is secured to each sheet 11 at points 17 and 19 approximately in the middle of the conductive sheets 11. This strap 15 has a preferred electrical length equal to approximately one-half wavelength at mid-band frequency. The dimension across both sheets, arranged end-to-end, including the spacing between them is in the range of $\frac{3}{8}$ to $\frac{5}{8}$ of the operating wave length.

In Fig. 2, there is shown more clearly the positioning of the strap 15 which, while being joined at outer ends to plates 11 at approximately the midpoints 17, 19, is spaced away from the sheets throughout the rest of its length by a small amount.

The strap 15 in conjunction with the antenna forms effectively a shunt reactance in parallel with the antenna. This reactance is high over the mid-band portion, similar to the action of a short-circuited quarter-wave stub. The reactance becomes inductive at frequencies below mid-band frequency and capacitive at frequencies above mid-band frequency. It is therefore possible by proportioning the strap 15 properly in its cross-sectional dimension or configuration to affect the impedance of the antenna, and give the antenna a highly desirable impedance characteristic over the band of frequencies desired. The voltage distribution in the strap 15 will always have a nodal point in the center of the strap, opposite the middle of the terminals 13.

In one embodiment of this antenna successfully tried out in practice which was designed for

the frequency band from 500 to 900 megacycles per second, the antenna had the following dimensions: The angle A in Fig. 1 was 70° , and the width across both sheets was $15\frac{1}{8}$ inches including a $\frac{3}{8}$ inch spacing between the sheets at the adjacent apexes, which is convenient spacing for terminating ordinary parallel-lay $\frac{3}{8}$ inch line. The strap 15 was $8\frac{1}{8}$ inches long and the center section was spaced $\frac{1}{8}$ of an inch from the sheet 11. The sheets 11 were made of $\frac{1}{2}$ inch brass, while the strap 15 was $\frac{1}{8}$ by $\frac{1}{2}$ inch brass. It will be seen that the spacing of the strap 15 from the sheets 11 varied between $\frac{1}{15}$ and $\frac{1}{27}$ of a wavelength for the band of frequencies for which the antenna was designed.

Fig. 3 graphically illustrates the frequency versus gain characteristic of the antenna of Fig. 1 under the foregoing conditions, compared with a simple half-wave dipole matched throughout the frequency band to 300 ohm output, the half-wave dipole considered as having a gain of unity; that is, being always zero on the decibel scale. It should be noted that the antenna exhibits a slowly rising gain characteristic with a maximum occurring at the upper end of the frequency band.

Fig. 4 illustrates the frequency versus standing wave ratio of the antenna of Fig. 1 under the foregoing conditions. The standing wave ratio is lowest near the middle of the band where the operating frequency gives approximately one wavelength across the width of both elements.

Figs. 5 and 6 graphically illustrate the azimuthal field patterns of the antenna of Fig. 1 at the two extremes of frequency at both ends of the band. These figures illustrate the desirable directional characteristics of the antenna over the entire band for which it is designed. In both illustrations the larger lobe occurs in the front of the antenna while the smaller lobe occurs in the rear of the antenna where the strap is located.

Fig. 7 shows an array of two dipole antennas 11 and 11' of the construction illustrated in Fig. 1 joined mechanically and electrically at the outer lower points of the upper set 11 and the outer upper points of the lower set 11', respectively designated 21 and 23. The dipoles of Fig. 7 are substantially identical to each other and to the dipole of Fig. 1. Straps 15, 15' identical with those described in connection with Figs. 1 and 2 are provided for each antenna dipole in the array. A short length of transmission line 25 is shown connected between the feed point 13 of the upper elements 11 and the feed point 13' of the lower elements 11'. The transmission line extending to the receiver or transmitter is coupled to the center 27 of the short section of transmission line 25.

Fig. 8 graphically illustrates the gain versus frequency characteristic of the antenna array of Fig. 7, when tested over a band of frequencies ranging from 500-900 mc., also compared with a simple half-wave dipole matched throughout the frequency band to 300 ohms, and considered as having a gain of unity. Comparing Fig. 8 with Fig. 3, it can be readily seen that a considerable increase in gain is obtained by use of the array shown in Fig. 7, and that a peak is exhibited in the upper end of the band.

Fig. 9 graphically illustrates the standing wave ratio versus frequency characteristic of the array of Fig. 7. An inspection of Fig. 9 and a comparison with Fig. 4 shows that the standing

wave characteristic is also altered and that the low point for the array is shifted upwardly.

Figs. 10 and 11 respectively show a graphical representation of the azimuthal field patterns of the antenna array of Fig. 7 for the low and high ends of the band for which they were designed. An inspection of Figs. 10 and 11 and a comparison with Figs. 5 and 6 will show that the field patterns are identical.

The resulting antenna, either with a single pair of elements or in an array, was found to be mechanically very stable due to the presence of the strap 15 joining the two triangular sheets and overcoming the difficulty of providing sufficient support encountered in prior art antennas supported by rigid feed lines joined at the apexes. The actual mounting brackets for fastening the antenna to the mast or reflector (not shown in the drawing) are preferably secured to the middle of the strap 15 which is a point of zero voltage.

Since the strap 15 is electrically conductive, and is connected at its mid-point to the antenna mast, not shown, the entire assembly can be grounded by grounding the mast, giving simple and effective lightning protection without the necessity for separate lightning arrestor devices.

Although conductive sheets 11 are shown in the figures of the drawing as being of solid material, the sheets 11 may have apertures therein or be constructed of conductors spaced apart, with the ends of such conductors electrically connected. The term "sheet" in this specification and the appended claims is deemed to include this perforated type of sheet.

Although there is illustrated and described an antenna having triangular sheet elements, it will be understood that by proper dimensioning, the same invention could be utilized in an embodiment having elements shaped like sectors of a circle, wherein the outer edges would be curved.

The antennas of the invention are particularly suitable for the reception of television and other signals requiring a broad band of frequency.

I claim:

1. A broad band antenna structure comprising two separate triangular sheets of conductive material having apexes of acute angles adjacent to each other, the dimension across both sheets being substantially one wave-length at mid-band frequency, a strap of conductive material, said strap having a length of substantially one-half one wave-length at mid-band frequency, the width of said strap being considerably narrower than both the length thereof and widest dimension of said sheets, said straps being connected to the centers of said sheets and supporting said separate sheets at the ends of said strap, said strap being closely spaced from said sheets, and terminals at said adjacent apexes of said sheets.

2. Broad band antenna structure comprising two separate triangular sheets of conductive material in the same plane, having apexes of acute angles adjacent to each other, the dimension across both sheets being substantially $\frac{2}{3}\lambda$ to $\frac{5}{6}\lambda$ at the operating frequency, a strap of conductive material, said strap having a length substantially $\frac{1}{3}\lambda$ to $\frac{5}{6}\lambda$ at the operating frequency, and being connected to and supporting said separate sheets at the ends of said strap, the width of said strap being considerably narrower than both the length thereof and the widest dimension of said sheets the center of said strap being physically spaced from said sheets a distance not sub-

stantially greater than $\frac{1}{15}\lambda$, and terminals at said adjacent apexes of said sheets.

3. Broad band ultra high frequency antenna structure comprising a plurality of triangular sheets of conductive material, each pair of said triangular sheets having apexes of acute angles adjacent to each other, the dimension across both sheets being substantially one wave-length at mid-band frequency, a strap of conductive material having a length of substantially one-half one wave-length at mid-band frequency the width of said strap being considerably narrower than both the length thereof and the widest dimension of said sheets, said straps being connected to each pair of said sheets at the ends of said strap, said strap being spaced a distance not substantially greater than $\frac{1}{15}\lambda$ from said sheets, and terminals at said adjacent apexes of said sheets.

4. Broad band ultra high frequency antenna structure comprising a plurality of similar triangular sheets of conductive material, each pair of said triangular sheets having apexes of corresponding angles adjacent to each other, the dimension across both sheets being substantially one wave-length at mid-band frequency, a strap of conductive material, having a length of sub-

stantially one-half one wave-length at mid-band frequency the width of said strap being considerably narrower than both the length thereof and the widest dimension of said sheets, said straps being connected to each pair of said sheets at the ends of said strap, said strap being spaced a distance not substantially greater than $\frac{1}{15}\lambda$ from said sheets, the outer lower points of each pair of said sheets being connected to the outer upper points of the next lower pair of said sheets, and terminals at said adjacent apexes of said sheets.
